US00D787190S

(12) **United States Design Patent** (10) **Patent No.:** **US D787,190 S**
(45) **Date of Patent:** **** May 23, 2017**

(54) **MAKEUP BRUSH**

(71) Applicant: **Worth Beauty, LLC**, Houston, TX (US)

(72) Inventors: **Steven C. Machiorlette**, Houston, TX (US); **Carol M. Martin**, Atlanta, GA (US); **Charles Michael Gayle**, Midlothian, VA (US)

(73) Assignee: **Worth Beauty, LLC**, Houston, TX (US)

(**) Term: **15 Years**

(21) Appl. No.: **29/540,966**

(22) Filed: **Sep. 29, 2015**

(51) LOC (10) Cl. **04-02**

(52) U.S. Cl.

USPC **D4/102**

(58) **Field of Classification Search**

USPC D4/102, 127, 130, 132, 133, 135, 138, D4/199; D28/4, 7, 8

(57) **CLAIM**

The ornamental design for a makeup brush, as shown and described.

DESCRIPTION

FIG. 1 is a front perspective view of a makeup brush according to the present design;

FIG. 2 is a front elevation view of the makeup brush shown in FIG. 1.

FIG. 3 is a rear elevation view of the makeup brush shown in FIG. 1.

FIG. 4 is a right side elevation view of the makeup brush shown in FIG. 1.

FIG. 5 is a left side elevation view of the makeup brush shown in FIG. 1.

FIG. 6 is a top plan view of the makeup brush shown in FIG. 1; and,

FIG. 7 is a bottom plan view of the makeup brush shown in FIG. 1.

The broken lines depict portions of the article that form no part of the claimed design.

1 Claim, 4 Drawing Sheets
